THREAD-ADVANCING REEL

Arthur L. Jackson, West Asheville, N. C., assignor
to American Enka Corporation, Enka, N. C., a
corporation of Delaware

Application April 16, 1948, Serial No. 21,385

1 Claim. (Cl. 28—71.5)

1 This invention relates to thread-storage, thread-advancing devices, and more particularly to a thread-storage, thread-advancing device adapted for use in the after-treatment of wet-spun rayon threads and the like.

In the art of continuous spinning, which usually involves the after-treatment of a freshly spun thread on a plurality of thread-storage, thread-advancing devices, there have been developed several basic types of thread-handling machines. One of these involves a pair of cylinders supported at one end and having their axes convergent in the direction of the unsupported end, and another of these in a reel-like structure comprised of interdigitating rods, half of which are mounted on one axis and half on another, the two axes being closely adjacent and convergent so that the thread, in passing along the reel, passes alternately from one set of rods to the other and so is caused to advance in a generally helical path.

Both of the foregoing types of thread-storage, thread-advancing devices have met with a considerable degree of commercial acceptance, but both of them are open to certain objections which have heretofore been regarded as necessary incidents to the operation of such apparatus. For example, in the use of the two-roller type thread-storage, thread-advancing device, the thread passes in a generally helical path around the two rollers. If breakage occurs, however, the thread tends to stick to one of the rollers and to wind around it so that very often before an operator can get to the unit to take corrective measures, a considerable amount of yarn is wrapped around the cylinder so that stoppage of the unit and a cleaning operation is necessary before the unit can be put back into operation.

Actually, from the point of view of thread breakage, the two-cylinder type of thread-storage, thread-advancing device is superior to the type involving interdigitating reels. However, for treatment purposes, the interdigitating-type reel affords the advantage that it is compact, easy to thread up and can be supported in cantilever fashion without the use of bearings having high load ratings.

It is proposed, according to this invention, to overcome the difficulties heretofore caused by thread breakage on a thread-storage, thread-advancing device, and to provide a thread-storage, thread-advancing device of the reel or cage type, which is characterized by a relative movement of its component parts which renders

the unit self-cleaning in the event of thread breakage.

It is an object of the present invention to provide a thread-storage, thread-advancing device composed of two cages which rotate in overlapping paths and wherein the surfaces of the two component cages move in opposite directions in the zones of overlap while the cages, as a whole, turn in the same direction.

10 Other objects and advantages of this invention will be apparent upon consideration of the following detailed description of the preferred embodiment in connection with the annexed drawings wherein:

15 Figure 1 is a view in side elevation of a thread-storage thread-advancing device constructed in accordance with the principles of the present invention;

20 Figure 2 is a view in elevation of the free end 20 of the thread-storage, thread-advancing device of Figure 1;

Figure 3 is a view in vertical section through the axes of the device of Figure 1; and

25 Figure 4 is a view in elevation of the driving end of the thread-storage, thread-advancing device of Figure 1.

Referring now in greater detail to the drawings, the thread-storage, thread-advancing device there shown is comprised of two reels or cages 10 and 11. The lower reel 10 is comprised of eight rods or bars 12, circumferentially spaced to define a generally cylindrical thread-supporting structure. The bars 12 at the left-hand end of Figure 1 are curved to define a spider 13, and the hub of this spider is attached to and supported from a drive shaft 14. While the spider 13 is illustrated as integral with the rods or bars 12 and formed by them, it is, of course, apparent that the spider 13 may be a separate structure. In any event, the hub of the spider 13 is attached to the drive shaft 14 by suitable means, such as the lock bolt 15 shown in Figure 1.

45 At the end remote from the spider 13, and shaft 14 is mounted in a bearing block 16 having a lower bifurcated end. The block 16 is pivotally mounted in a rectangular slot 17 of a bearing plate 18. The angular position of the block 16 and hence the shaft 14 is adjustable by operation of an adjusting bolt 19. The bolt 19 is in threaded engagement with a sleeve 20 and is rotatably mounted in another sleeve 21.

The right-hand end of the shaft 14, as it is viewed in Figure 1, is provided with a spur gear

22. This gear is keyed to the shaft 14, and it is through the gear 22 that the shaft 14 is driven.

The driving of the gear 22 is effected through an idler gear 23 which is mounted for rotation on a stud 24 that is supported in a socket in the plate 18. The gear 23 meshes with a gear 25 which is keyed to a shaft 26 which is journaled in the block 18.

Shaft 26, at its end remote from the gear 25, is attached to a disc or plate 27 of circular cross section and, mounted in this plate, are the eight bars 28 that constitute the reel 11. A spacing collar 29 is attached to the shaft 26 between the disc 27 and the plate 18. A protective shield 30 separates the reels 10 and 11 from the driving mechanism therefor and this shield is provided with apertures to receive the collar 29 and the bolt 19.

It is to be noted that the reels 10 and 11 are of equal diameter and that the respective component rods thereof are equally spaced circumferentially. The reel 11 is arranged with its axis $x-x$ horizontal, and the reel 10 is arranged with its axis $y-y$ inclined upwardly from right to left as it is viewed in Figures 1 and 3. In other words, the axes $x-x$ and $y-y$ are convergent in the direction of the unobstructed ends of the reels. The magnitude of this inclination is, of course, somewhat adjustable by operation of the bolt 19. The details of this operation will be more apparent after a consideration of the structural details of the adjusting mechanism. Upon reference to Figures 2 and 4 it will be observed that the sleeves 20 and 21 are each mounted on oppositely, radially extending pivot pins. The pivot pins 31 and 32, that extend from the sleeve 20, are mounted for pivotal movement in the tines 33 and 34 respectively of the lower bifurcated end of the bearing block 16. Thus, the sleeve is rendered rotatable or rockable about the common horizontal axis of pins 31 and 32. Similarly oppositely radially extending pins 35 and 36 support the sleeve 21 for rocking movement about their common horizontal axis. The pins 35 and 36 are held by supporting straps 37 and 38 respectively which are attached to the back surface of the plate 18 adjacent the rectangular slot 17.

The bearing block 16 is of greater thickness at its upper end than at the lower bifurcated end and oppositely extending horizontal pins 39 and 40 support the block from its end of greater thickness for rocking movement within the slot 17.

When adjustments of the angular position of the shaft 14 are to be made, bolt 19 is turned and, since the threaded portion of the bolt engages sleeve 20 while the end of the bolt is mounted for free rotation in the sleeve 21, bearing block 16 is rocked either clockwise or counterclockwise about the axis of the pins 39 and 40 depending upon which way the screw 19 is turned. The adjustments are of such slight magnitude that the gears 22 and 23 continue to mesh properly throughout the entire desired range of adjustment.

The reels 10 and 11 are so arranged that their respective peripheries overlap in a zone between the axis of the shaft 14 and the axis of the shaft 26, as can be clearly seen in Figure 3. However, in view of the fact that both of them are driven in the same direction and at the same speed, it is necessary initially to establish the proper angular position of the reels on their respective shafts in

order that the bars or rods 12 may interdigitate with the bars 28, as is indicated in Figure 3.

In operation, the device previously described is started by connecting the shaft 26 to a suitable power source so that that shaft is driven in a clockwise direction as it is viewed in Figure 2. The operator then takes the thread received from a spinning source, a supply body or a preceding thread-storage, thread-advancing device and winds a loop around the two cage elements 10 and 11 near the right-hand end of those elements as they are viewed in Figure 1. The closed loop so formed is fed axially from right to left, as viewed in Figure 1, at a rate which is a function of the convergence of the axes $x-x$ and $y-y$. The take-up speed is, of course, controlled by the rotational speed of the shaft 26. In view of the fact that the gears 22, 23 and 25 are all of the same size, both of the cages 10 and 11 will rotate at the same speed. Since they are equal in diameter, the peripheral speed of each will be the same. When the closed loop has progressed axially to the left-hand end of the cages, as they are viewed in Figure 1, the operator breaks the thread and leads it to the next stage of the operation; the loop used during the threading up is taken off the free end of the device and discarded.

Treating liquids may be applied to the thread during the passage across the thread-storage, thread-advancing device, and to that end discharge devices may be disposed above the reel, and collection devices therebelow, so that the treating liquid may be recirculated.

If now reference is made to Figure 2, it is noted that, although both cages are rotating in a clockwise direction, as viewed in that figure, the path of movement of the rods 12 intersects the path of movement of the rods 28 from A to B, and that, in this zone of intersection, the rods 28 are moving to the left while the rods 12 are moving to the right. Consequently, the rods are moving in opposite directions in that zone of overlap, and this opposite movement produces an important advantage in the event of thread breakage. Suppose, for example, that the thread breaks at point C and has a tendency to fall over the adjacent bar 12c which it has just left; this, in the case of the prior art interdigitating reels, could produce a serious tangle. In the present case, however, the broken end merely rides with the bar 12c until it is struck by one of the oppositely-moving bars 28, at which time it is knocked loose from its prior position and is caused to hang free from the lower cage 10 where convenient corrective measures can be taken by the operator. In the event that the break is not instantly discovered, all that happens is the production of waste in the collection trough below the cage 11 where the waste can be easily and conveniently removed without the necessity of stopping the thread-storage, thread-advancing unit for cleaning.

It should be noted that, although the cage 10 is supported from one end while the cage 11 is supported from the other, the advantages of cantilever construction are fully retained due to the fact that the supporting shaft for the cage 10 passes centrally through the cage while the supporting shaft for the cage 11 extends from one end thereof.

The spider 13, by being made integral with the component bars of the cage 10, provides a rounded surface where the bars are curved radially inwardly so that removal of the thread from the left-hand end of the cage 10, as it is viewed in

Figure 1, is easy, and flanges, such as are produced by the plate or disc 27 of cage 11, are avoided at the discharge end of the unit.

The foregoing description has been concerned with but a single embodiment of the present invention, but it is apparent that various modifications and alterations of the illustrated and described form of the invention are possible within the scope of the appended claim. For example, more than two cages or reels may be employed in which their peripheries overlap in a zone between their axes. It is only necessary to vary the number of bars or rods and their circumferential spacing so that they interdigitate properly.

What is claimed is:

A thread-storage, thread-advancing device comprising a pair of reels, each reel including a plurality of circumferentially spaced bars, the bars of one of said reels being curved radially inwardly at one end to form a supporting spider, the bars of the other of said reels being supported by a disc, said disc and spider being at the opposite ends of the respective reels, a reel supporting and driving shaft extending from the spider centrally through that reel, another supporting and driving shaft extending from the disc away from the reel, said shafts being supported from one end only thereof with the shaft

axes convergent in the direction of the unsupported ends of the shafts and so spaced that the path of movement of the bars of one reel overlaps the path of movement of the bars of the other reel in a zone lying between the axes of the two shafts, a bearing plate to support said other supporting and driving shaft and a bearing block to support said reel supporting and driving shaft, said bearing block being pivotally mounted on said bearing plate, means to pivot said bearing block to change the convergence of said shaft axes and means for driving the shafts in the same direction and at the same speed.
